UNITED STATES PATENT OFFICE.

BENJAMIN F. BAIN, OF PITTSBURGH, AND FRANK L. SHAFFER, OF BELLEVUE,
PENNSYLVANIA; SAID SHAFFER ASSIGNOR TO SAID BAIN.

MECHANICAL TOY FOOT-BALL PLAYER.

1,324,783.

Specification of Letters Patent.

Patented Dec. 16, 1919.

Application filed May 3, 1919. Serial No. 294,475.

To all whom it may concern:

Be it known that we, BENJAMIN F. BAIN, a resident of Pittsburgh, in the county of Allegheny and State of Pennsylvania, and 5 FRANK L. SHAFFER, a resident of Bellevue, county of Allegheny, and State of Pennsylvania, have invented a new and useful Improvement in Mechanical Toy Foot-Ball Players, of which the following is a specification.

The invention relates to mechanical toys of the kind in which a figure of a man is provided with a spring propelled leg arranged to contact with and propel a ball 15 and thus give an imitation of a player kicking a foot-ball.

The object of the invention is to provide a toy of the character described in which means for holding the spring propelled limb 20 in retracted position is released by the ball to be propelled; in which the ball actuated means for releasing the limb is so located that when it is actuated by the ball the latter will be in position to be properly contacted by the released limb; which is provided with means for directing or guiding the ball to such release means; in which the limb retaining and release means are so arranged as to produce a minimum amount of 25 friction so that the limb can be released by a very light ball,—one which can be propelled to a considerable distance; and, in general, a toy of the character described 30 which is of substantial construction and reliable in operation.

In the accompanying drawings Figure 1 is in part a side elevation and in part a central vertical longitudinal section through the toy; Fig. 2 is a plan view of the toy; and 40 Fig. 3 is a section on the line 3—3, Fig. 1.

1 represents a suitable base for supporting the toy, said base in the embodiment illustrated being formed of sheet metal having a top, sides and ends. 2 represents the 45 figure which preferably will be made to simulate a foot-ball player, having one leg 3 rigid with the body and secured to the base in any suitable way, such as soldered or by means of rivets. The body 2 may be formed 50 of any suitable material, but for lightness and cheapness is preferably formed of stamped sheet metal as illustrated. This has a further advantage that a body so formed

is hollow for housing the means for actuating the pivoted limb.

The leg 5 is pivotally mounted to the body and means are provided for giving it a rapid forward movement. Various arrangements for this purpose can be provided. The drawings show the leg 5 secured to the 60 outer end of a shaft 6 which is rotatively mounted in the body as shown, and has its opposite end extending through the body where it is provided with a washer 7 and cross pin or the like for preventing endwise 65 displacement of said shaft. Intermediate its ends said shaft is bent to form a crank 9 to which is connected one end of a helical tension spring 10, the opposite end of which is secured to the body, such as by passing 70 said end through a hole in the wall of the hollow body and back through another hole in said wall. A cross brace 13 is provided adjacent to the shaft 6, to stiffen the hollow body at this point and to also serve as a 75 stop to be contacted by the crank 9, as shown in Fig. 3, and thus limit the rotation of shaft 6, the forward movement of the leg 5 and bring said leg to a sudden stop.

The catch mechanism for holding the leg 80 5 in retracted position comprises a shaft 14 located just above the base and extending transversely thereof, slightly to the rear of the figure 1, having its end mounted in ears 15 punched from the top wall of the base 85 and turned to upright position. Secured to this shaft is a catch member 16 provided at its forward end with the upturned portion 17 forming the catch proper arranged to engage the toe of the foot 18 of the movable leg as shown in Fig. 1. Secured to this 90 catch member 16 and projecting forwardly immediately underneath the top wall of the base is the catch lever 18, whose forward end is arranged to be engaged by a loop 19 pivotally mounted by means of transverse 95 pin 20 extending through ears 21 upturned from the top wall of the base forwardly of the figure 1. Secured to the loop 19 is a trigger comprising a pair of rearwardly extending arms 22 curved slightly upwardly and spaced apart as shown so that the foot 100 of the movable leg 5 can pass therebetween. This trigger device is also provided with a forwardly extending portion 23 which serves 105 as a counterbalance for the arms 22 and ar-

ranged to contact with the top of the base in order to limit the movement of the loop 19 in a rearward direction. The catch member 16 is provided with an upturned portion 24 to be engaged by the heel of the kicking foot when the latter is pulled backwardly, in order to lift the forward end of catch lever 18 to engage it with the trigger loop 19 when setting the device. The forward 10 end of the lever 18 is beveled, as shown at 25, in order to automatically engage it with the trigger loop 19 when the upturned portion 24 is pressed backwardly. A stirrup 26 depends from the top wall of the base rearwardly of the trigger loop 19 and serves to prevent the forward end of the catch lever 18 from dropping below the lower edge of the base.

The trigger arms 22 are in such position 20 that when the ball, shown as 27, is dropped onto the same, to release the leg 5, the ball will be in such position that it will be squarely hit by the foot on leg 5 in its forward motion. In order to guide this ball 25 into proper relation to the trigger arms 22 so that it will be squarely hit by the forwardly moving foot, the arms 28 of the figure are extended forwardly and the hand portions thereof connected by a ring 29, which is in such position that when the ball 30 is dropped through the same it will strike squarely between the trigger arms 22, and therefore be in position to be squarely hit by the forwardly moving foot. Preferably this 35 ring will be open on the forward side, as shown at 30, to allow a cord or twine to be attached to the ball for retrieving it, which cord will escape through the opening 30 when the ball is kicked.

In order that the ball be propelled the 40 greatest distance it is necessary that it be very light, the ball preferably being a small hollow celluloid ball of the kind used in playing the game of "ping pong". Inasmuch as the ball is very light the trigger mechanism must be very sensitive in order 45 to be released by such light weight ball. The mechanism illustrated is of this character being so arranged as to offer the minimum amount of friction between the trigger loop 19 and catch lever 18. It will be noted 50 that the pressure of the movable foot when it engages the catch 17 is almost entirely straight forward. In other words, the principal component of this force is horizontal 55 and only a slight component thereof is downward. Consequently when the movable foot is locked in position, as shown in Fig. 1, there is only a very slight downward pressure of the forward end of the catch lever 18 on the trigger loop 19. Also, 60 the trigger device is nicely balanced so that a very slight weight falling on the trigger arms 22 is sufficient to oscillate said trigger device to release the trigger loop 19 from

the catch lever 18 and permit the locked foot to be released.

In the use of the device the mechanism is set by pulling backwardly on the movable leg 5. In this backward movement the 70 heel of the movable foot contacts with the upturned portion 24 on the catch, thus lifting the catch portion 17 to bring it in front of the toe of the foot and lifting the forward end of the catch lever 18, which, on account of its beveled end, slips past the loop 19 and allows the latter to swing underneath the end of said lever. This locks the movable leg in retracted position, and puts the spring 10 under greater tension. The 80 ball is then dropped through the ring 29, and strikes the trigger arms 22 and on account of the nice balance of the trigger device and the very slight friction between the loop 19 and lever 18, said trigger device is 85 oscillated to disengage loop 19 from lever 18, thus releasing the leg 5 which snaps forwardly so rapidly that it catches the ball before it has time to move on the trigger arms 22, and propels the same in the manner 90 of a kicked foot ball.

The toy described is of simple construction, and is so arranged that it is actuated automatically by the delivery of the ball thereto through the guide ring 27. The toy 95 is of substantial construction, reliable in operation, and the parts are so arranged that the movable foot will contact squarely with the ball and thus propel it to a maximum distance. Obviously, the design or 100 character of the figure can be changed to suit the fancy of the maker or user.

We claim:

1. A mechanical toy comprising a figure provided with a spring propelled pivoted limb, a catch for holding said limb in retracted position, and a ball actuated device for releasing said catch and so located that the ball when in position to actuate the release device is in position to be impelled by the released limb.

2. A mechanical toy comprising a figure provided with a spring propelled pivoted limb, a catch for holding said limb in retracted position, a ball actuated device for releasing said catch and so located that the ball when in the act of actuating said release device is in position to be impelled by the released limb, and means for directing said ball to the trigger device.

3. A mechanical toy comprising a figure provided with a spring propelled pivoted limb, a catch for holding said limb in retracted position, and a balanced device for releasing said catch, said release device comprising a pair of spaced arms to be contacted by the ball and in position to have foot of the released limb pass therebetween.

4. A mechanical toy comprising a figure provided with a spring propelled pivoted

limb, a catch for holding said limb in retracted position, a balanced device located forwardly of the figure, and a lever connected to the catch and arranged to be engaged by the release device, said parts being so arranged that the stress of the pivoted limb on said catch produces a minimum amount of friction between the lever and the release device.

10 5. A mechanical toy comprising a figure provided with a spring propelled pivoted limb, a pivotally mounted catch for holding the limb in retracted position and located rearwardly of the figure and so arranged that the stress of the pivoted lever exerts mostly a horizontal stress on the pivot of said catch, a lever connected to said catch and projecting forwardly, and a release device pivotally mounted forwardly of the figure and having a portion arranged to engage with and become disengaged from the forward end of said lever by a horizontal

movement, whereby the friction between said release device and lever is reduced to a minimum.

25 6. A mechanical toy comprising a figure provided with a spring propelled pivoted limb, a catch device for holding said limb in retracted position, pivotally mounted rearwardly of the figure, a forwardly projecting horizontal lever connected to said catch, and a release device pivotally mounted forwardly of the figure and provided with spaced projecting arms to be contacted by the ball, and an oppositely projecting counter-balance and with a downwardly projecting member arranged to engage the forward end of the catch lever by a horizontal movement.

30 35 In testimony whereof, we have hereunto set our hands.

40 BENJAMIN F. BAIN.
FRANK L. SHAFFER.
